(57) **CLAIM**

The ornamental design for a fluid distribution equipment, as shown and described.

DESCRIPTION

The patent or application file contains at least one drawing executed in color. Copies of this patent or patent application

publication with color drawing(s) will be provided by the Office upon request and payment of the necessary fee.

1.-4. Fluid distribution equipment

1.1 Top Plan View

1.2 Top, Front, Right Perspective View

1.3 Bottom Plan View

1.4 Bottom, Left, Rear Perspective View

1.5 Front Elevational View

1.6 Right Side Elevational View

1.7 Rear Elevational View

1.8 Left Side Elevational View

2.1 Top Plan View

2.2 Top, Front, Right Perspective View

2.3 Bottom Plan View

2.4 Bottom, Left, Rear Perspective View

2.5 Front Elevational View

2.6 Right Side Elevational View

2.7 Rear Elevational View

2.8 Left Side Elevational View

3.1 Top Plan View

3.2 Top, Front, Right Perspective View

3.3 Bottom Plan View

3.4 Bottom, Left, Rear Perspective View

3.5 Front Elevational View

3.6 Right Side Elevational View

3.7 Rear Elevational View

3.8 Left Side Elevational View

4.1 Top Plan View

4.2 Top, Front, Right Perspective View

4.3 Bottom Plan View

4.4 Bottom, Left, Rear Perspective View

4.5 Front Elevational View

4.6 Right Side Elevational View

4.7 Rear Elevational View

4.8 Left Side Elevational View

The area inside the central broken line circle in reproductions 1.1, 1.2, 2.1, 2.2, 3.1, 3.2, 4.1, and 4.2 forms no part of the claimed design. The broken lines in the reproductions of design 2 represent portions of the fluid distribution equipment that form no part of the claimed design; the parts shown by blue color in the reproductions of design 4

(Continued)

represent portions of the fluid distribution equipment that form no part of the claimed design.

**1 Claim, 32 Drawing Sheets
(6 of 32 Drawing Sheet(s) Filed in Color)**
